UNITED STATES PATENT OFFICE.

GARFIELD A. WOOD, OF DETROIT, MICHIGAN.

DUMPING TRUCK.

1,406,131.

Specification of Letters Patent. Patented Feb. 7, 1922.

Original application filed December 26, 1916, Serial No. 138,762. Divided and this application filed May 9, 1918. Serial No. 233,544.

To all whom it may concern:

Be it known that I, GARFIELD A. Wood, a citizen of the United States, and residing at Detroit, in the county of Wayne and State 5 of Michigan, have invented a new and Improved Dumping Truck, of which the following is a specification.

This application is a division of my application for U. S. Letters Patent, S. N. 138,762, 10 filed December 26, 1916.

The present invention relates to means for dumping the contents of truck bodies by lifting the front ends thereof upwardly about pivots located at the rear end of the 15 chassis.

It has been customary heretofore to use hydraulic hoisting mechanism for this purpose, the parts being so arranged that the cables leading to the front end of the body 20 led down between the side bars of the chassis when the body was lowered. The space between the side bars is often needed for other parts which form essential elements of the chassis unit and it has proven a matter of 25 difficulty to provide clearance for the cables and associated body arms. The primary object of the present invention is to provide a cross arm construction of such character that it may be cheaply and readily manufac- 30 tured and assembled, and may be employed in greater lengths than was feasible in former constructions, whereby the connections of the cables to the body may be made outside of the side bars and whereby the use 35 of separate additional equalizing bars or devices is avoided. The whole hoist and body construction is thus rendered more readily applicable to the chassis of different trucks.

In the drawings, Figure 1 is a fragmentary 40 side view of a motor truck showing a preferred embodiment of my invention. Fig. 2 is a vertical section looking from the right in Fig. 1. Fig. 3 is a longitudinal section through the upper end of the piston rod.

1 indicates the side bars of the vehicle to the rear end of which are secured brackets 2 bearing pivots 3, about which the body 4 may be swung vertically for dumping purposes. The body may be provided along 45 its lower side with longitudinal frame pieces 5 so arranged as to rest, when in lowered

position, either on the side frames 1 or on special chairs carried thereby. This general construction is well known.

At a point slightly forward of the front 55 end of the body is a supplementary frame comprising angle bars 8, preferably having their horizontal flanges facing one another, which are bolted at 9 to the side bars and have their ends projecting beyond the latter. 60 Mounted upon the supplemental frame in any suitable manner is a hoisting cylinder 10, the upper end of which is surrounded by an expansion chamber 11 in free communication therewith. Also supported on the 65 supplemental frame in any preferred manner, for example, by being attached directly to the base 12 of the hoisting cylinder, is a gear pump 13 which may be driven from the propeller shaft 14 by clutch mechanism 15, 70 the details of which need not here be described. The cylinder encloses a piston (not shown) of customary construction having a hollow perforated piston rod 16 that extends out through a stuffing box 17 located at the 75 upper end of the cylinder—as this piston rod serves as a part of the storage reservoir for oil whereby the hoisting is accomplished, its upper end is closed by a diaphragm 18 (Fig. 3). 80

The piston rod is perforated above the diaphragm to receive the hollow sleeve 20 through which a pivot bolt 21 in turn passes; the bolt also passes through the bars 22 that extend equal distances in opposite directions 85 transversely of the vehicle and have their ends connected by bolts 23 upon which supporting straps 24 for pulleys 25 are hung. In the preferred construction, the pulleys 90 are located outwardly beyond the corresponding side bars. The front end of the body has secured thereto in any suitable manner body arms 26, which are preferably located so that their lower ends, at least, normally extend down outside of the 95 adjacent side bar, and which may have their intermediate portions bowed forwardly as indicated at 28 (Fig. 1) and connected to the members 5 by braces 29. Anchored to the ends of the front cross bar, for example, by 100 means of eye bolts 30, are cables 31 which pass over the pulleys 25 and have their other

ends attached to the lower end of the corresponding body arm, preferably by means of a shackle 32 and pivot 33.

The pump, upon being actuated, draws the stored oil from the expansion chamber and the space above the piston down through the pipe 34 and expels it through a passage (not shown) into the cylinder at a point beneath the piston, which thereupon rises and tilts the body. Any tendency to apply the forces to one side of the body in excess of those applied to the other side, such as might be caused by warping or standing on uneven ground, is compensated for by slight pivotal movements of the cross bars 22 when the body is lowered; the body arms 26, passing down outside of the side bars 1, do not interfere with the clutch or other members which may be located in this region and yet may sink far enough to allow the use of a relatively short hoisting cylinder. At the same time, the lower ends of the body arms, which follow quite closely the line of the cable attached thereto, are subjected to very little bending stress, and the members 29 co-act with the body and the upper portions of the body arms to form a truss whereby the greater bending stresses in the upper portions of the side arms are taken.

30 I claim:-

1. In combination with the frame of a vehicle, a body pivoted adjacent the rear end of said frame to tip, hydraulic hoisting means for the front end of the body, said hoisting means including an upwardly projecting cylinder, a hollow piston rod reciprocable in said cylinder, the upper end of said piston rod being perforated transversely, two cross bars, one on each side of the piston rod, a pivot passing through the perforation in the piston rod and through the cross bars, means for joining the outer ends of said cross bars to form a cross-arm, and tension members supported by the last mentioned means and arranged to transmit lifting stress to opposite sides of the front end of the body.

2. In combination with the frame of a vehicle, a body pivoted adjacent the rear end of said frame to tip, hydraulic hoisting means for the front end of the body, said hoisting means including an upwardly projecting cylinder, a hollow piston rod reciprocable in said cylinder, the upper end of said piston rod being perforated transversely, a hollow sleeve passing through the rod, a pivot passing through the sleeve and projecting therefrom at each end, a cross arm including two cross bars, one on each side of the piston rod, said pivot also passing through the cross bars, means for joining the outer ends of the cross bars, and tension members supported by the last mentioned means and arranged to transmit lift-

ing stress to opposite sides of the front end 65 of the body.

3. In combination with the frame of a vehicle, a body pivoted adjacent the rear end of said frame to tip, hoisting means for the front end of the body, said hoisting means 70 including an upwardly projecting guide, a member reciprocable in said guide, a tiltable cross-bar construction associated with the upper end portion of said reciprocable member, said cross-bar construction including a plurality of members connected together near their outer end portions and extending transversely of the vehicle, and tension members supported by the end portions 75 of said members and arranged to transmit lifting stress to opposite side portions of the adjacent end of the body.

4. In combination with the side bars of a vehicle, and a body pivoted near the rear end thereof to tip, an upright guide centrally 80 mounted on the vehicle forward of the body, a member reciprocable in respect thereto and projecting upwardly therefrom, a cross bar supported by the reciprocable member and tiltable transversely of the vehicle, pulleys 85 supported on the cross bar outside of the vertical planes through the corresponding side bars and rotatable about axes extending transversely of the vehicle, and cables passing over the pulleys and connected to the 90 body outside of said side bars.

5. In combination with the frame of a motor vehicle, a body pivoted adjacent the rear end thereof to tip, an upright cylinder 100 forward of the front end of the body, a piston rod reciprocable therein, a cross arm carried by the upper end of said rod and comprising two separate transversely extending bars, one forward and one back of the transverse central longitudinal plane of the piston rod, bolts joining the outer ends of the bars, pulleys supported by said bolts, and cables passing over said pulleys and operatively connected to the body, whereby the latter is tilted as the piston rod rises. 105

6. In mechanism of the class described, an upstanding cylinder, a piston rod reciprocable therein and projecting from the upper end thereof, a cross arm comprising two separate bars located on opposite sides of a longitudinal central plane of the piston rod, means for supporting the cross arm on the piston rod, said means including a pivot the axis of which extends transversely of and substantially intersects that of the piston 120 rod, bolts joining the outer ends of the bars, pulleys supported on the outer ends of said bars, and cables passing over the pulleys.

7. In combination, a cylinder, a piston rod reciprocable therein, a cross arm actuated thereby, said cross arm including two portions one on each side of a longitudinal central plane of the piston rod, bolts joining

said portions at their outer ends, straps passing over said bolts and spacing the portions apart, and pulleys carried by said straps.

5. A vehicle having a tiltable body, an up-standing guide adjacent said body, a member reciprocable in said guide for tilting the body, a tiltable cross-arm supported by the reciprocable member and including two

members arranged substantially symmetrically with reference to said reciprocable member and joined together near their outer end portions, and tension elements for transmitting lifting stress from said outer end portions to spaced points on the body, where- 15 by the latter may be tilted.

GARFIELD A. WOOD.
